CONVERTIBLE LUGGAGE RACK AND BENCH

Raymond H. Reiss, Deal, N. J., assignor to Northern Furniture Company, Sheboygan, Wis., a corporation of Wisconsin.

Application September 20, 1932
Serial No. 633,933

1 Claim. (Cl. 155—41)

This invention relates broadly to furniture and more specifically to a combined seat or bench and a luggage rack.

Luggage racks have heretofore been proposed consisting of strips of fabric extending transversely between side frame members mounted upon legs which are pivoted to one another in the form of an X and capable of folding together. In hotel bedrooms, for instance, such luggage racks frequently stand at the foot of a bed and luggage carelessly placed thereon or handled often mars the foot board of the bed.

One object of the invention is a luggage rack having a portion which, when the rack is occupied, will protect a piece of furniture next to which the rack stands.

Another object of the invention is a luggage rack which is also capable of use as a bench or seat.

It is also an object of the invention to provide a convertible luggage rack and bench or seat in such fashion that a seat member, when in use as such, hides the supporting surface for the luggage and when luggage is supported protects an adjacent piece of furniture from damage.

The invention also seeks a combined bench and luggage rack which is both sightly in appearance and practical from the standpoint of manufacture and use.

These and other objects of the invention and the means for their attainment will be more apparent from the following detailed description, taken in connection with the accompanying drawing, illustrating a preferred embodiment thereof, and, in which:

Figure 1 is a view, in perspective, showing the combined seat and luggage rack when in use as a bench.

Figure 2 shows the luggage rack with the seat raised to protect a neighboring piece of furniture.

Figure 3 is a view in section taken on the line 3—3 of Figure 1, looking in the direction of the arrows.

Figure 4 is a detail view in section, taken on the line 4—4 of Figure 3.

The invention is shown as comprising four relatively fixed legs 2, one at each corner, fixed to longitudinally and transversely extending frame members 4 and 6, respectively, the top of the frame member and the top of the legs lying in the same horizontal plane and the legs being braced in suitable fashion, as, for instance, at 8.

Extending between the longitudinal frame members 4 and with their upper surfaces 9 in the plane of the top edge thereof, are slats 10

preferably of wood, shown as oval in cross-section in Figure 4, on which the luggage rests. To the upper surface 9 of these slats 10 are secured strips or facings 12 of wear resistant material, such as iron or steel bars or plates somewhat shorter than the slats and secured thereto in any desirable manner as by the countersunk screws 14. The surfaces of the ends of the wearing strips 12 may be curved downwardly or bevelled as at 15 so that no sharp edges may be presented to the luggage as it is placed thereon which would damage the same.

The wear resistant supporting surface of this article of furniture, therefor, lies above the surface of the wooden frame and the frame is thus protected against damage by a piece of luggage placed thereon.

Covering or overlying the luggage supporting surface of the rack is a cover or seat 16 which when down, as shown in Figures 1 and 3 serves as a seat and transforms the baggage rack into a bench. When open as shown in Figure 2, the cover 16 may rest against the foot of a bed or other piece of furniture and protect the same against damage by a piece of luggage resting on the luggage supporting surface or surfaces 12. Such seat 16 may be either plain wood or other substance or it may be upholstered, as desired.

The cover 16 is conveniently secured, as by hinges 17, to the frame of the luggage rack along one of its longer sides whereby it may be moved through an angle in excess of 90° about its line of pivot. As shown the hinges are secured to the upper ends of the legs 2, thus spacing the cover from the frame and affording space above the upper surface of the frame for the wear resistant strips 12. Along the side opposite to the hinges, the cover 16 is conveniently provided therebeneath with buffers or buttons 18 of yielding nonmetallic material, such as rubber, which not only supports the cover in spaced relation from the frame and in substantial parallel relationship thereto but cushions the shock of the cover on the frame should it be allowed to fall.

It will thus be seen that an extremely practical luggage rack has been provided which is sturdy and durable and offers protection to neighboring furniture. At the same time, when not in use as a luggage support, the luggage rack may afford a sightly appearance and serve as a bench.

Various modifications will occur to those skilled in the art in the composition, disposition and configuration of the component elements going to make up the invention as a whole and no limita-

tion is intended by the phraseology of the foregoing description or illustrations in the accompanying drawing except as indicated in the appended claim.

5 What is claimed is:—

A convertible luggage rack and bench comprising, in combination, legs, a frame carried thereby comprising longitudinal and transverse members, slats extending between the longitudinal frame members, facing strips of wear resistant material secured to the upper surfaces of their respective slats forming a luggage support-

ing surface above the horizontal plane of the top of said frame members, slats and legs, a cover of the same size and shape as the frame, hinge means securing an edge of the cover to the frame whereby said cover may rotate through an angle of at least 90° and buttons of yielding non-metallic material secured to the lower surface of the cover which together with the hinges support said cover in spaced relationship to the frame to present the appearance of a bench.
